US00D366855S

United States Patent [19]

Deelen

[11] Patent Number: Des. 366,855

[45] Date of Patent: Feb. 6, 1996

[54] FLOWERPOT WITH WATER SAUCER

Pots, Plant Husbandry Boxes.

[75] Inventor: R. J. Deelen, Zwanenburg, Netherlands

Primary Examiner—Alan P. Douglas
Assistant Examiner—Cathron B. Matta

[73] Assignee: Ypma International B.V., Zwanenburg, Netherlands

[57] CLAIM

[] Term: 14 Years

The ornamental design for a flowerpot with water saucer, as shown and described.

[21] Appl. No.: 35,582

DESCRIPTION

[22] Filed: Mar. 2, 1995

FIG. 1 is a perspective view of the claimed invention showing my design which is the subject of this invention; FIG. 2 is a side view of the claimed invention; FIG. 3 is a top view of the claimed invention; FIG. 4 is a bottom of the claimed invention; FIG. 5 is a perspective view of the flower pot portion of my invention to show the detail of said flowerpot. FIG. 6 is a side view of the flower pot portion of my invention to show the detail of said flowerpot; FIG. 7 is a bottom view of the flower pot portion of my invention to show the detail of said flowerpot; FIG. 8 is a top view of the flower pot portion of my invention to show detail of said flower pot; FIG. 9 is a perspective view of the water saucer portion of my invention to show the detail of said water saucer; FIG. 10 is a side view of the water saucer portion of my invention to show the detail of said water saucer; FIG. 11 is a top view of the water saucer portion of my invention to show the detail of said water saucer; and, FIG. 12 is a bottom view of the water saucer portion of my invention to show the detail of said water saucer.
